United States Patent

Des. 236,156

Patented July 29, 1975

236,156

VIBAPHONE

Clair O. Musser, 12997 Blairwood Drive,
Studio City, Calif. 91604

Filed May 29, 1973, Ser. No. 364,807

Term of patent 14 years

Int. Cl. D17—04

U.S. Cl. D56—1 E

FIG. 1.

FIG. 2.

FIG. 3.

FIG. 4.

FIG. 5.

FIG. 6.

FIG. 1 is a front, top and right side perspective view of a vibraphone showing my new design;

FIG. 2 is a top plan view;

FIG. 3 is a front elevational view;

FIG. 4 is a right side elevational view;

FIG. 5 is a rear elevational view; and

FIG. 6 is a left side elevational view.

I claim:

The ornamental design for a vibraphone, substantially as shown and described.
